UNITED STATES PATENT OFFICE.

JAMES HENRY GRESSOM, OF MINNEAPOLIS, MINNESOTA, ASSIGNOR TO
OWEN T. DOUGHERTY, OF MINNEAPOLIS, MINNESOTA.

WAGON-STAKE STANDARD.

SPECIFICATION forming part of Letters Patent No. 739,542, dated September 22, 1903.

Application filed November 6, 1902. Serial No. 130,261. (No model.)

To all whom it may concern:

Be it known that I, JAMES HENRY GRESSOM, a citizen of the United States, residing at Minneapolis, in the county of Hennepin and State 5 of Minnesota, have invented certain new and useful Improvements in Wagon-Stake Standards, of which the following is a specification.

My invention relates to wagon-stake standards, and has for its object the production of 10 a standard of special formation enabling it to be cheaply manufactured and to require a minimum of metal in its construction, thus cutting down its weight, while obtaining maximum strength and durability by reason 15 of the peculiar fashion and arrangement of its elements. I accomplish the objects set forth by means of the parts and their association illustrated in the accompanying drawings, in which—

20 Figure 1 represents a side perspective view. Fig. 2 is a side view in vertical section; and Fig. 3 is a top plan view of the upper portion or block, showing the preferred form of the stake hole or socket.

25 Like numerals refer to like parts throughout the several views.

In the drawings, numeral 1 marks a wagon-bolster of any size or form having a rounded termination 2. About this end of the bolster 30 passes the base-band 3, U-shaped and having the end plates 4 and 5 (see Figs. 1 and 2) pierced with suitable bolt or screw holes 6, and, further, the band is sometimes provided with dropped or extended edge portions 7 and 35 8, having screw-holes 9 10, and by means of the various screw-holes the base-band is secured to the rounded end of the bolster, as illustrated. Rising from the end plates 4 and 5 of the base-band are the inclined side pieces 40 or legs 11 and 12, stiffened and strengthened by the ribs 13 and 14 and formed usually integral, with the base-band below and the socket-block 15 above. These elements may be welded together, as well as cast. It will 45 be noted here that the hole 16 through the socket-block 15 is in the shape of a horseshoe, and owing to this peculiar shape it is possible to get a stake out easily if it should happen to break in the socket-hole, for a 50 broken stake could be worked back and forth

in the square end of hole 16 and any split portions turned around and drawn out in the round end of the hole; but an unbroken stake would be kept from turning about by the peculiar shape of the hole.

55

Numeral 17 refers to the inclined front piece or brace of my invention. This piece extends from the socket-block 15 downwardly and outwardly to the bend of the base-band 3 around the end 2 of bolster 1. Front piece 60 17 is curved both lengthwise and laterally, presenting outwardly a rounded surface and inwardly a concave surface. The lower end of the curved front piece 17 fits the rounded end of the bolster and merges into the base-band 3, as shown. At its upper part front piece 17 merges into block 15; but at the top of the block it is extended above the block and provided with an orifice 19, which is for the purpose of tying ropes or hooking chains 70 to hold any portion of a load on the wagon. The piece through which orifice 19 passes is entirely out of the way, and as it forms a solid part of the block and is not merely riveted on it is not likely to be broken off, even 75 if a heavy log or stick of timber should fall upon it.

Considering Fig. 2, it will be observed that there is a lug 20 formed at the lower end and upon the hollow or inner side of front brace 80 17. Lug 20 may be pierced by a screw-hole 21 and act to secure front brace 17 more permanently to the end of the bolster. It will be observed from the drawings that the standard is given an unusually long base-area in 85 connection with the bolster, and this feature adds materially to the rigidity and strength of the whole.

I am aware that numerous wagon-stake standards have been patented, and I make 90 no general claim to such articles.

What I claim is—

A wagon-stake standard consisting of a single piece of metal, comprising a hollow socket-block at the top merging into an outwardly 95 and downwardly curving concave front piece, the said front piece extending above the said block and having the orifice 19 above the block, the lower and concave end of the front piece adapted to engage the rounded end of 100

a bolster and having a lug 20 fixed to the top of the bolster, the said front piece merging into the base-band 3 by which the end of the bolster is inclosed, and the straight inclined rear braces 11 and 12 having their ends merged into base 3 and into said block, as shown and described.

In testimony whereof I affix my signature in presence of two witnesses.

JAMES HENRY GRESSOM.
